DOUCHE

Samuel T. Matsinger, Philadelphia, Pa.

Application October 20, 1936, Serial No. 106,651

2 Claims. (Cl. 128—266)

The invention relates to a douche and more especially to a vaginal insufflator.

The primary object of the invention is the provision of a douche of this character, wherein the bulb forms the container for the powder having medicinal properties so that such powder can be injected into the vaginal tract for treatment thereby doing away with a separate container or receptacle, the douche being of novel construction and is readily and easily handled for the working thereof.

Another object of the invention is the provision of a douche of this character, wherein the bulb thereof constitutes the container for the medicinal substance and when such bulb is compressed it will inject the powder into the vaginal tract for the treatment of infections and there is no liability of the powder being removed from the tract on the expanding of the bulb after contraction thereof and also the contents of the bulb can not spill when the douche is not in use.

A further object of the invention is the provision of a douche of this character, which is simple in construction, thoroughly reliable and effective in its operation, strong, durable, readily and easily operated and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a side elevation of the douche constructed in accordance with the invention.

Figure 2 is a vertical longitudinal sectional view thereof showing the same applied.

Figure 3 is a fragmentary enlarged sectional view showing the valved air inlet of the douche.

Figure 4 is a sectional view on the line 4—4 of Figure 3 looking in the direction of the arrows.

Figure 5 is a vertical sectional view through the bulb showing the medicament introduced thereto.

Similar reference characters indicate corresponding parts throughout the several views in the drawing.

Referring to the drawing in detail, the douche comprises a tube 10, preferably made from hard rubber although it may be made from metal or any other suitable material, having at its outer

end a shield holder 11 which is made fast to the tube 10 and also is centrally bored and into this bore is threaded the nozzle 12 which is also made from hard rubber although it may be made from metal or any other material suitable in the use of the douche.

The tube 10 intermediate its ends has fitted therein a cut-off valve 13 having a hand grip 14 so that it can be manually turned for the opening and closing of said valve.

Formed with the tube is an extension 15 providing an air inlet passage 16 and this extension 15 carries a valve cage 17 in which is a floating valve 18 allowing the ingress of air but checking the escapement of air through the cage when the 15 douche is being operated.

On the other end of the tube 10 remote from the nozzle 12 is a compressible rubber bulb 19, it having a neck 20 carrying an outwardly flared or truncated conical shaped mouth piece 21, 20 which is fitted on and snugly embraces the tube 10 when the bulb is attached thereto. When the bulb is detached from the tube 10 the same can be filled through the mouth 21 with medicated powder 22 as within a container 23, the 25 powder being hand poured within the bulb when detached from the tube. On the filling of the bulb with the powder 22 or other like substance it is made secure on the tube 10 and when the bulb is compressed the powder will be injected through the nozzle 12, the article being a vaginal douche for the treatment of infections thereto.

The holder 11 has fitted therewith a shield 24, which is of soft rubber and is susceptible of removal from the holder, the said shield being 35 adapted to close the mouth of the vaginal tract in the use of the douche.

What is claimed is:

1. A douche of the character described comprising a tube, a shield holder on one end of said tube, a flexible shield removably fitted with the holder, a nozzle extending from said holder, an extension on said tube, an air inlet valved cage on said extension, and a removable bulb on the other end of the tube and having a flared mouth. 40

2. A douche of the character described, comprising a tube, a shield holder on one end of said tube, a flexible shield removably fitted with the holder, a nozzle extending from said holder, an extension on said tube, an air inlet valved cage 50 on said extension, a removable bulb on the other end of the tube and having a flared mouth, and a cut-off valve fitted in said tube.

SAMUEL T. MATSINGER.
